HEATING DEVICE

Filed July 30, 1926

INVENTOR

INVENTOR

UNITED STATES PATENT OFFICE.

PAUL M. KLEIN, OF CEDARHURST, NEW YORK.

HEATING DEVICE.

Application filed July 30, 1926. Serial No. 125,845.

The present invention relates to heating devices in general and particularly to an improvement over the kind described and claimed in my copending application for 5 Letters Patent Serial Number 105,871, filed April 30th 1926, for fuel burner and to the process of producing heat.

One of the objects of this invention is to provide means for efficiently preparing 10 liquid fuel for the purpose of burning it and, when thus prepared, properly mixing it with the required amount of air to produce perfect combustion.

Another object of my invention is the construction of a device which combines the fuel convertor or generator with means for intimately mixing or carburetting air to produce a highly combustible mixture.

Another object of my invention is to provide in such device means for preventing direct heat from coming in contact with the generator or convertor while permitting indirect or radiated heat to produce within said convertor, a gradual change of the fuel 25 from its liquid to a gaseous state.

Another object of my invention is to provide air supply means constructed in such a manner as to create a constant layer of air to surround the convertor, thereby preventing 30 direct heat from reaching the latter.

Another object of my invention is to make provisions in the air supply means for constantly agitating the air or imparting to said air, a rotary motion while passing over the 35 outer surface of said convertor, thereby not only causing an intimate mixture between the gasified fuel and air, but also assuring a uniform distribution of the combustibles.

Another object of my invention is to provide 40 a plurality of means for changing the relations between said air supply means and said convertor, thereby facilitating the changing of the air spaces between the various parts for producing a proper combustible mixture for any given draft condition.

Still further objects will become more evident from the following description of my device in connection with the accompanying drawings, forming an illustrative part 50 of my invention, but not intended in any event to limit it to the design shown.

In order to create a better understanding of the subject matter of this invention, I consider it essential to explain the principle 55 of producing heat by liquid fuel.

Efficient burning of fuel for the production of heat depends greatly upon the quality of the combustibles and upon their preparation before they are combusted. It is well known that liquid fuel, even in its most refined state, will not burn efficiently unless it is intimately mixed with a sufficient quantity of air or oxygen.

An intimate mixture of fuel with air can only be achieved by breaking up the fuel into 60 a fine mist, or better, by converting it into gas, which latter, will then readily mix with air, due to the fact, that the affinity between two like elements is greater than between 65 two elements of various qualities (density).

The conversion of liquid fuel into gaseous fuel, particularly where fuel oil of a gravity lower than 42° Baumé is concerned, can be best accomplished in a convertor which combines means for gradually preheating the 70 oil, thereby making it more fluid, other means for spreading the now preheated fuel into a thin layer or film, and means for subjecting that film to the proper amount of indirect heat, which will cause the gasification, 75 or partial gasification, of the film of the fuel.

Be it understood, of course, that this conversion can only take place in an air excluding chamber which prevents air from coming in contact with the fuel while in its 80 liquid state.

The reason for preventing direct heat from coming in contact with the fuel convertor will become obvious when it is considered that the excess of heat supplied to the 90 oil to be gasified may cause the formation of an excessive carbon deposit within the convertor, which is undesirable.

The thus produced gasified fuel should be 95 intimately mixed with the proper amount of oxygen. This is best accomplished by providing an air supply which is agitated while mixing with the fuel gases.

In the above manner the air is carburetted by the fuel gases and then the carburetted 100 mixture is supplied with additional oxygen, which is preferably also agitated, while being added to the combustible.

It is needless to say that the proper amount of air mixed with the given fuel 105 gas is essential to produce proper mixture and a consequent proper combustion. It is therefore essential in a device of this kind that the air supply is capable of being regulated.

From the following description of my device, in connection with the drawings, the essentials of my construction will be readily discernible.

5 Referring to the drawings, Figure 1 is a partial cross sectional view taken on line 1—1 of Figure 2.

Figure 2 is a bottom view of my device.

10 Figure 3 is a support employed in my device for attaching it to the existing grates of the furnace in which the device is installed.

15 Figure 4 is a bottom detail view of the distributor of my device and,

15 Figure 5 is a cross sectional view through a modified form of my device.

20 Referring to the figures, numeral 1 denotes the grates of an existing furnace upon which is placed the base support 2, shown in detail in Figure 3.

25 The base support 2 is provided with peripheral notches 3 for receiving clamping bolts 4, which pass through clamping bars 5. By tightening bolts 4, the grates of the furnace are tightly held together between the base support and the clamping bars, whereby the base support is fixed onto the grates.

30 It will be noted in Figure 3, that the base support is provided with slots 6 for receiving attaching bolts 7 (see Fig. 1). There will be also seen, in Figure 3, cut-outs 8 for providing a free air passage for the purpose which will be explained later.

35 Upon the base support rests the burner base 9 to which is attached at its bottom an overflow retainer 10 by means of bolts 11. The overflow retainer and the base is securely held together by these bolts and form substantially one member.

40 The overflow retainer is provided with a central hub 12 which is hollow and adapted to receive a supply pipe or tube 13, which latter is adjustable within the hub and is 45 clamped tight in the desired position by means of set screws 14. The overflow retainer is also provided at its bottom with a boss 15 for accommodating the end of the overflow pipe 16.

50 In the base there will be observed drip holes 17 for permitting the discharge of superfluous oil into the overflow retainer.

55 At the bottom portion of the burner base there will be seen a plurality of curved veins 18 which impart to the air passing through the central opening 19 of the base a rotary motion in the direction shown by arrows in Figure 2.

60 The base is further provided with cylindrical extensions 20 upon which rests a manifold 21. While I have shown in Figure 1 a manifold which comprises two supply inlets, it is understood that a manifold of less inlets or more inlets may be constructed.

As will be seen in Figure 1, the central portion of the manifold comprises a cylindrical or conical downwardly opening spout 22 which is preferably provided with helical veins 23.

70 Within this spout 22 there is seen the fuel convertor which comprises a closed chamber, consisting of a cylindrical portion 24, a cover member 25, a well 26 and a distributor 27. The latter is provided with a threaded hub to which is attached supply pipe 13. The latter supports the entire convertor.

75 The central portion of the distributor 27 is drilled to provide a passage of liquid fuel, which is supplied by means of oil ports 28 into the well 26. Just above the oil ports 28, the central portion of the distributor 27 is provided with a threaded hole, which is engaged by a double bolt 29. The latter is adapted to hold together all the parts of the convertor. The upper extension of a bolt 29 is adapted to clamp down the manifold 21. Thus the entire burner parts are united and prevented from vibrating while in operation.

80 It will be seen that the cup or well 26 is provided with an internal rib 30, by means of which the well may be turned when screwed together with the upper extension of distributor 27.

85 The well is a substantially hollow cylinder adapted to receive liquid fuel which is preheated through radiated heat. The pre-heating of the oil is essential for making the oil more liquid than it would be in atmospheric temperature. The oil in the well is preheated to a temperature ranging from 90 200° to 300° F.

95 The cylindrical portion of the convertor is provided with an annular inward extension 105 31, which is adapted to not only retard the flow of oil, while in its process of being gasified, but is also designed for leading the oil, spread in a film form over the outer surface of the oil well, in radial inward direction. 110 In other words, instead of spreading the oil radially outwards, the oil is forced to flow toward the center of the distributor, while and if in its liquid state. This oil, before 115 its conversion into gasified fuel is caused to drip into an auxiliary well 32 provided in the distributor and from there, if still liquid, will flow into another auxiliary well 33.

120 The prepared fuel will escape from within the convertor by means of radial slots 34, provided in the lower face of the cylindrical member 24, which rests upon the upper face of the distributor.

125 The arrangement of the cylindrical member 24 can be readily observed at the bottom view, shown in Figure 4, where it will be seen that the annular inward extension 31 reduces the outflow area for the fuel to a small central opening, indicated at .34'. Through this opening the fuel, either gaseous 130

ous or liquid, is directed towards the center of the distributor. This manner of construction becomes fairly important for the reason, that in installing my device, it is necessary 5 that the distribution of the fuel is uniform over the circumference of the distributor. The different passages, through which the fuel has to travel, concentrate the fuel toward the center of the distributor and therefore 10 fore to the smallest available circumference, from which it is spread outwards, while in its gaseous state.

In installing my device, all parts are preferably made level, which is accomplished 15 by the adjustment of set screws indicated at 35 in Figure 2.

In the beginning of operation the parts of 20 the burner are not hot enough to cause the gasification of the oil and it is essential that, 25 while in fluid state, the oil is distributed evenly when it drips down through the slots 34 into the dish-shaped portion of the base.

The distance between the upper face of 30 the grates and the upper face of the distributor, upon which rests cylindrical part 24, I 35 may term the "critical distance." It is essential in any burner that such distance between the point of distribution and between the point of resting is made as short as possible. The shorter the distance, the easier 40 it is to properly install the device, and the easier it is to cause even distribution of the fuel while in its liquid state, and consequently also its distribution while in its 45 gaseous state.

Installation.

Referring to Figure 1, the base support 2 is placed upon the grates. By means of 40 clamping bars 5 and clamping bolts 4, the base support is tightly joined with the grates, thus making it practically immovable. The base is now attached to the base support by means of attaching bolts 7, which 45 are first not tightened down completely, in order to permit the leveling of the base by means of set screws 35, which bear against the solid portions of the base support. I 50 preferably level the device by first inserting supply pipe 13 and attaching thereto the distributor and oil well 26, which I temporarily screw down to the distributor, while leaving out the cylindrical part 24 and the cover 25. The upper edge of the oil 55 well serves as leveling surface.

When satisfied that the oil well is level a check may be made by setting a level upon the distributing surface of the distributor.

Now the attaching bolts 7 are clamped 60 tight and again a check is made of the leveled oil well and distributor. Now the oil well is removed, the cylindrical part 24 set upon the distributor, the oil well replaced and the cover attached.

By means of bolt 29 the cover 25 is tight-

ly clamped down against the cylinder member 24, which again seats tightly against the distributing surface of the distributor.

Now the manifold 21 is placed upon extensions 20. It will be observed, that between the seating surface of the manifold and the extension 20, there are provided rings 36 which are exchangeable as will be explained later.

When the burner is thus assembled a layer 75 of clay, not shown in the drawing, is placed over the grates, being supported by a sheet of metal or screening, so that the space between the outer circumference of the burner base and the walls of the furnace is completely filled in, to prevent air from passing therethrough.

I preferably line the wall of the furnace with refractory brick, not shown, which retains heat and permits a constant radiation 85 of heat toward the burner, particularly during periods of low burning.

Operation.

To start the burner, oil is admitted 90 through the supply pipe into the oil well 26 from which it flows evenly over the upper edge thereof and spreads into a thin film over the outer surface of the well. From the lower edge of the well it drips down upon 95 the ledge formed by extension 31 of the cylindrical member 24 and drips down into the central auxiliary well 32 of the distributor. Having filled this auxiliary well, the oil reaches the upper edge of the well and 100 descends into the outer auxiliary well 33. From here it passes over the distributing surface of the distributor at the points where the cylindrical member 24 is slotted. From here it flows down the undercut portion of 105 the distributor and drips into the dish-shaped portion of the base.

The oil retained in the base is now ignited by means of a torch, or its equivalent, 110 while the oil supply is cut off. Through the heat thus generated, the manifold is heated and the temperature of the air drawn through the manifold is thereby also raised. The arrows shown in the manifold indicate 115 the direction of the air passing therethrough.

Upon reaching the center of the manifold, the air is passed through a plurality of veins 120 provided in the downwardly directed center portion 22 of the manifold. The veins, being helically shaped, impart a rotary motion to the air which passes around the entire outer surface of the convertor.

When reaching the escapes 34, provided in the cylindrical portion 24, the air will, so-to-speak, suck out the gasified fuel and mix 125 with it. In this manner the air is carburetted. Due to the turbulent motion of the air a very thorough mixture is produced between the air and the gases. Moreover, the revolving tendency of the air will cause the 130

gases to travel in conjunction with the air. In this manner the fuel gases are spread around the entire circumference of the distributor, which eliminates the concentration of escaping gases at the point where slots 34 are provided. This is a rather important feature for the reason that a uniform distribution of the combustible gases is accomplished.

10 The preparation of the fuel for the purpose of burning, before combustion, may be explained as follows: The air passing through the manifold is heated to a high degree. It passes over, and forms a hot air cushion between the convertor and the center portion 22 of the manifold. The heated air imparts its indirect heat to the cylindrical portion 24 of the convertor, heating it to a temperature ranging from between 500° 15 to 850° F. The heat imparted to the cylindrical portion 24 is radiated towards the film of liquid fuel, descending over the outer circumference of the well 26, thereby gasifying it. Through further radiation of the 20 heat towards the center of the convertor, the oil, in the well is preheated to a temperature ranging from between 200° to 300° F., which causes the oil to become more fluid than when it reaches the well.

25 It will be seen from the above that no direct heat is permitted to affect the convertor, and that the heat within the convertor is so low that, while permitting the gasification of the oil, it will not cause the formation of 30 solid carbon within the convertor, which would be the case if the converter would be subjected to direct heat of sufficient intensity.

35 Needless to say that air is completely excluded from the interior of the convertor, since the presence of air would seriously affect the proper conversion of liquid fuel into gaseous fuel.

40 When the carburetted air reaches the outlet passage between the lower portion of the distributor and the lower portion of the central member of the manifold, it is met by another supply of air which passes between the lower face of the burner base and the overflow retainer. The air passing beneath the burner base and between veins 18 45 towards the center opening of the base is caused to rotate, and its velocity, is successively increased when traveling from its entrance point to its discharge point.

50 The air is directed towards the lower face of the distributor and, being deflected thereby, issues at practically right angles into the carburetted mixture.

55 The resulting forces of the air supplied through the manifold and the air supplied from below the base cause the combustibles to take a path corresponding to the outline of the dish-shaped upper surface of the base.

60 In this manner the base is subjected to a

considerable amount of heat which in turn is imparted to the air passing from below the base as an additional air supply.

It is essential for efficient burning that the proper amount of air is supplied to the 70 gasified fuel. In consequence thereof, it is necessary that the various parts may be adjusted, so as to increase or decrease the spaces through which air is admitted. The air space between the upper edge of the 75 base and the lower edge of the distributor may be adjusted by an up or down movement of pipe 13. Correspondingly, the manifold has to be adjusted in up or downward direction. This is accomplished by inserting 80 various sized rings under the manifold seat as indicated at 36.

When the proper adjustment is reached the upper nut of bolt 29, which passes through the manifold, is tightened down so 85 as to prevent vibration of the burner parts during operation.

Modifications.

It is obvious that while I have described 90 the construction shown in Figures 1, 2, 3 and 4 that modifications of construction may be made without departing from the principal ideas involved.

A modified design is shown in Figure 5 in 95 which a base support 36 is illustrated, upon which rests the base 37, being held together with the support by attaching bolts 38. The construction of the base is somewhat different, as it now consists of two parts, the outer 100 member 39 and the inner adjustable member 40, which latter corresponds to the base shown in Figure 1, with the exception that it is adjustable relative to member 39. This construction provides an additional air space, 105 indicated at 41, for supplying still more oxygen after the combustion of the gases has taken place.

The overflow receptacle 42 is again attached in the same manner to member 40, 110 as was explained in connection with Figure 1. In this case however, member 42 is supported by a tube 43, to which it is clamped by means of set screw 44 or any other suitable means. Tubing 43 is adjustable within hub 115 45, supported by ribs 46, extending from the cylindrical portion of member 39. Tubing 43 is held in its position by means of set screw 47.

Within the tubing 43 there is adjustably 120 mounted supply pipe 48 which again is held in position by a set screw 49. The overflow pipe 50 is connected to a boss provided in overflow retainer 42.

Attached to pipe 48, in the same manner as 125 explained above, is a convertor 51 of the same construction described in connection with Figure 1.

The manifold 52 in this case consists of 130 a single air chamber, and is attached to

the base by means of bolt 53, bearing with its nut against a bar 54.

In the downward end of the manifold are again provided helical veins 55. At the 5 lower portion of member 40 are also provided veins 56. The operation of the device is identical with that described in connection with Figure 1, with the exception that additional air is permitted to enter the 10 burner at the annular slot 41 mentioned before. The adjustment of this slot is readily made by lowering or raising tubing 43.

Adjustment of the air space between member 40 and the convertor 51 and between 15 member 40 and the manifold is achieved in the same manner as explained before in connection with Fig. 1.

It is evident that various other constructions may be provided to accomplish the same 20 result of preparing liquid fuel for burning within an air excluding convertor, which is constantly surrounded by a cushion of agitated, heated air, which prevents direct heat from reaching the convertor.

25 By these combined means a perfect conversion of the fuel is accomplished, which facilitates perfect mixing of the fuel with the air and therefore results in perfect combustion, without the formation of carbon 30 deposits on any of the parts exposed to the flame or on any of the parts in which the conversion of the fuel takes place.

Simultaneously the construction of the air supply means, causing the air to rotate at 35 the point of issue, assures perfect distribution, as the air supplied through the manifold induces the spreading of the escaping fuel over the entire surface of the distributor, and the air issuing from underneath the distributor enhances, through its rotary motion, the distribution of the gases. The even distribution of the combustibles assures a uniformly spread flame over the entire surface of the burner, and beyond the 45 burner proper, in radial outward direction. The circular flame thus produced covers practically the entire heating surface, generally provided and depended on in the construction of furnaces for burning other than liquid fuel. Through this arrangement 50 therefore a higher over-all efficiency of a heating plant is accomplished.

Adhering to the principles involved in my construction, I reserve for myself the right 55 to make changes and improvements in my design.

I claim:

1. A heating device, comprising a fuel convertor and air supply means completely 60 enclosing the former, said fuel convertor forming a substantially closed chamber having a plurality of evenly distributed means for the escape of converted or gasified fuel, and means within said chamber for causing the liquid fuel to change its direction of flow

successively, radially outwards and radially inwards, and to spread into an easily evaporative film, thus facilitating the conversion of liquid into gaseous fuel, said conversion being produced by radiant heat intercepted by a layer of air surrounding said convertor. 70

2. A heating device, comprising a fuel convertor and air supply means completely enclosing the former and causing the formation of an air layer about the entire convertor, said fuel convertor forming a substantially closed chamber having a plurality of evenly distributed means for the escape of converted or gasified fuel, and means within 75 said chamber for causing the liquid fuel to change its direction of flow successively, radially outwards and radially inwards, and to spread into an easily evaporative film, thus facilitating the conversion of liquid into 80 gaseous fuel, said conversion being produced by radiant heat intercepted by a layer of air surrounding said convertor. 85

3. A heating device, comprising a fuel convertor, and means for causing air to pass 90 and contact with the latter's entire outer surface, said fuel convertor forming a substantially closed chamber having a plurality of evenly distributed means for the escape of converted or gasified fuel, and means within 95 said chamber for causing the liquid fuel to change its direction of flow successively, radially outwards and radially inwards, and to spread into an easily evaporative film, thus facilitating the conversion of liquid into 100 gaseous fuel, said conversion being produced by radiant heat intercepted by a layer of air surrounding said convertor.

4. A heating device comprising a fuel convertor, and means for causing air from two 105 directions to pass and contact with the entire outer surface of said convertor, said fuel convertor forming a substantially closed chamber, having a plurality of evenly distributed means for the escape of converted or gasified fuel, and means within 110 said chamber for causing the liquid fuel to change its direction of flow successively, radially outwards and radially inwards and to spread into an easily evaporative film, thus facilitating the conversion of liquid into 115 gaseous fuel, said conversion being produced by radiant heat passing through a constantly agitated layer of air surrounding said convertor. 120

5. A heating device, comprising an air excluding fuel convertor, and means for causing an agitated air cushion to surround the outer surface of the latter, said fuel convertor forming a substantially closed chamber, having a plurality of evenly distributed means for the escape of converted or gasified fuel, and means within 125 said chamber for causing the liquid fuel to change its direction of flow successively radially outwards and to spread into an easily evaporative film, thus facilitating the conversion of liquid into gaseous fuel, said conversion being produced by radiant heat passing through a constantly agitated layer of air surrounding said convertor. 130

and radially inwards and to spread into an easily evaporative film, thus facilitating the conversion of liquid into gaseous fuel, said conversion being produced by radiant heat passing through a constantly agitated layer of air surrounding said convertor.

6. A heating device, comprising a substantially closed, air excluding fuel convertor, and means in close proximity thereto for directing agitated air to pass by its outer surface from two opposite directions, said fuel convertor forming a substantially closed chamber, having a plurality of evenly distributed means for the escape of converted or gasified fuel, and means within said chamber for causing the liquid fuel to change its direction of flow successively radially outwards and radially inwards and to spread into an easily evaporative film, thus facilitating the conversion of liquid into gaseous fuel, said conversion being produced by radiant heat passing through a constantly agitated layer of air surrounding said convertor.

25 7. A heating device, comprising a fuel convertor, air supply means surrounding the latter, other air supply means below said convertor, both of said air supply means adapted to direct air to pass over the outer surface of said convertor, said fuel convertor forming a substantially closed chamber, having a plurality of evenly distributed means for the escape of converted or gasified fuel, and means within said chamber for causing the liquid fuel to change its direction of flow successively radially outwards and radially inwards and to spread into an easily evaporative film, thus facilitating the conversion of liquid into gaseous fuel, said conversion being produced by radiant heat passing through a constantly agitated layer of air surrounding said convertor.

8. In a heating device, a fuel convertor comprising a substantially closed, air excluding chamber, containing fuel preheating means, fuel retarding and fuel distributing means, an air supply member surrounding said convertor, and conveying air over its outer surface, and preventing direct heat from coming in contact with said convertor, while permitting the latter to be subjected to indirect heat, air supply means disposed below said convertor, and means provided with said air supply means for imparting a rotary motion to the air passing therethrough.

60 9. In a heating device, a fuel convertor for changing liquid fuel into gaseous fuel, which comprises a substantially closed, air excluding chamber, containing a fuel well for preheating fuel, means for spreading the liquid fuel to a thin film which is readily converted into gaseous fuel, means for retarding the flow of fuel, means for subjecting the fuel to indirect heat, means for dis-

tributing the converted fuel and means for directing the fuel, during the process of its conversion, radially inwards.

10. In a heating device, a fuel convertor, having means for preheating liquid fuel, means for forming it into a film, means for subjecting the fuel to radiated indirect heat, means for retarding its flow, means for directing the passage of fuel in radial inward direction and means for distributing the fuel.

11. In a heating device, a fuel convertor as per claim 10, air supply means surrounding said convertor and causing the formation of a constantly moving air cushion about said convertor, thereby preventing direct heat from coming in contact with the convertor, means for imparting a rotary motion to the air provided in said air supply means, an air supply member disposed below said convertor, means provided with said air supply member for imparting a rotary motion to the air passing therethrough, and means for changing the relation between said convertor, said air supply means and said air supply member for adjusting the air spaces between these parts.

12. In a heating device, the combination of a generator and carburetter, comprising an air excluding fuel convertor having means for retaining, preheating and spreading into a thin film liquid fuel, means for subjecting the spread fuel to indirect heat for the purpose of gasifying it, means for causing the fuel to flow in radially inward direction, means for retarding the flow of fuel and means for distributing it, air supply means, surrounding said convertor, provided with means for imparting a rotary motion to said air, and serving for premixing or carburetting said air with the converted fuel escaping from said convertor, means for supplying additional air to the carburetted mixture, said latter air supplying means having provisions for imparting a rotary motion to said additional air, and a plurality of means for facilitating changing the relative positions of said two air supply means and said convertor, for the purpose of changing the air spaces between these parts.

13. In a heating device, air supply means, a substantially closed fuel convertor disposed within said air supply means and spaced therefrom by a constantly moving air cushion, preventing direct heat from reaching said convertor, the latter comprising means for preheating liquid fuel, means retarding its flow while subjected to indirect heat and thus converted into gas, and means permitting the escape of converted fuel within said air supply means and before reaching open space.

14. In a heating device, air supply means, a substantially closed fuel convertor disposed wholly within said means, and separated

therefrom by a constantly moving air cushion preventing direct heat from reaching said convertor, the latter comprising an air excluding chamber containing means for retaining, means for spreading to a thin layer and means for changing the flow direction of liquid fuel while the latter is subjected to the influence of indirect heat.

15. In a heating device as per claim 14, 10 the lower edge of said air supply means

substantially coinciding with the lower edge of said convertor, the latter provided with escape means for the converted fuel, arranged within said air supply means and disposed above the lower edge of said convertor. 15

Signed at New York in the county of New York and State of New York this 29th day of July A. D. 1926.

PAUL M. KLEIN.
